Primary Examiner — Jae Liang

Assistant Examiner — Samantha Lynne Brodowski

(74) Attorney, Agent, or Firm — Banner & Witcoff, Ltd.

CLAIM

The ornamental design for a bag, as shown and described.

DESCRIPTION

FIG. 1 is a top, front, left perspective view of a bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dotted broken lines represent stitching that forms no part of the claimed design. The even-length broken lines depicting the remainder of the article show features that form no part of the claimed design.

1 Claim, 7 Drawing Sheets
